UNITED STATES PATENT OFFICE

NORMAN L. SNOW, OF NEW CANAAN, CONNECTICUT, ASSIGNOR TO DIAMOND POWER SPECIALTY CORPORATION, OF DETROIT, MICHIGAN, A CORPORATION OF MICHIGAN

BOILER CLEANER

Application filed September 15, 1923, Serial No. 663,003. Renewed July 24, 1931.

This invention relates to boiler cleaners and refers more particularly to boiler cleaners of the general type in which the blower pipe is provided with a plurality of nozzles distributed throughout its longitudinal length and through which steam or other cleaning fluid is discharged against the boiler tubes or other surfaces to be cleaned. One of the objects of the invention is to provide a construction of this general character in which the valve for controlling the supply of cleaning fluid to the blower pipe during certain portions of rotative movement of the pipe can be formed integral with or rigidly connected with the blower pipe. Because of the long length of the blower pipe in this type of boiler cleaner, it is necessary to support the pipe from the boiler tube. Under the heat of the boiler there is a different rate of expansion of the boiler and its tubes than that of the boiler setting. This has heretofore prevented the use of a valve formed integral with or rigidly secured to the blower pipe. In the present invention the parts are so constructed and arranged that the use of a valve integral with or rigidly secured to the blower pipe is permitted. The invention further resides in the provisions for flexibility and movement of the blower pipe and its associated valve with reference to the head in which the blower pipe is swivelled, and in such further features of construction and arrangements of parts, as are hereinafter set forth.

35 In the drawings in which various modifications are shown;

Figure 1 is a vertical sectional view through one embodiment of my invention.

40 Figures 2 to 5 both inclusive are similar views showing modifications of the structure shown in Figure 1.

45 Describing first in detail the particular form shown in Figure 1, 20 designates the blower pipe which is provided with a plurality of nozzles 21 distributed throughout its

longitudinal length so as to discharge jets of steam against the boiler tubes 22. This blower pipe projects through a wall box 23 mounted in the boiler wall 24 and its inner end is supported by suitable brackets from the boiler tubes 22. 50

Turning movement to the pipe 20 is imparted by means of a sheave wheel 25 over which extends a chain 26 so that as the chain 26 is pulled, it will rotate the blower pipe 20 and direct the jets from the nozzles 21 against different portions of the boiler tubes. Steam to the pipe 20 is furnished through the inlet 27 which opens into the blower head 28. Within a casing or housing 28' of this head is located a sleeve 29 having a port 30 cooperating with the port 31 in the sleeve or pipe extension 32. It will be noted that this pipe extension 32 as well as the blower pipe 20 are screw-threaded into the sheave wheel 25 so that in effect the port 31 is formed in a valve member that is in fixed relation to the blower pipe. Therefore, as the latter is rotated the port 31 will register with the port 30 so that at certain predetermined rotative positions of the blower pipe 20 it will be open to steam or like supply through the ports 30 and 31 and head 28 and inlet 27, while at other positions the supply of steam or the like to the blower pipe 20 is automatically cut off. 60 65 70 75

Owing to the warping movement of the blower pipe 20 due to difference in expansion and to various other causes, the construction as so far described would be inoperative for any practical purposes since the valve member 32 would bind in the sleeve 29, but in the present novel construction, this difficulty is overcome in the following manner. The sleeve 29 at its inner end has a spherical head 33 with seats on a spherical bearing block 34 on which it rocks to take care of any rocking movement. The bearing block 34 is itself slidably mounted to take care of any vertical or lateral movement between the blower pipe 80 85 90

20 and the head 28, which latter is secured by bolts 36 or the like to the wall box 23. At its outer end there is provided an end thrust bearing 37 and a steam tight connection is made by employing a corrugated type of flexible joint such as is produced by the corrugated flexible member 38. It will thus be seen that by the novel construction and mounting of the valve member and its supports it is possible to form the movable valve member 32 rigid with the blower pipe 20.

10 In the modification shown in Figure 2, the blower pipe 20 is continued out to form the movable valve member 46 and this valve member 46 is mounted in a sleeve 47 which sleeve is connected at each end to the blower head 28a by means of corrugated flexible members or diaphragms 49. An end thrust bearing 50 is provided, which bearing is formed in a 20 slidable seat 51, so that in this construction as well as in that shown in Fig. 1, movement in every direction is provided for.

15 In Figure 3 is shown a still further modification including a blower head 28b and associated therewith is a conical valve head 57 seating in a conical valve seat 58 formed in the header or goose-neck 59. This conical valve 57 is rigidly connected to the blower pipe 20 but the latter itself is formed in two 25 parts connected by a flexible diaphragm 60. By this arrangement any deflection of the blower pipe 20, as by the warping of the boiler tubes 61 on which the blower pipe is mounted by brackets 62, is prevented from 30 being transmitted to the movable valve member 57 because of the flexibility in the blower pipe itself.

20 In Figure 4, 28c represents the blower head, the general arrangement of the valve 57 and the conical valve seat 58 in the goose-neck 59 being similar to that shown in Figure 3. The blower pipe 20 in this case is formed of two 40 separate sections which are connected together by a driving lug 63 which has sufficient clearance to permit of some play. Vertical or lateral movement is taken care of by a thrust bearing 64 while any rocking movement is taken care of by a spherical bearing 65 mounted in a seat 66 which is itself slidingly 45 mounted to take care of vertical or lateral movement.

45 A still further modification is shown in Figure 5 in which the blower pipe 20 is provided with a telescopic arrangement in the form of a slip joint 82 to take care of any longitudinal movement of the blower pipe 20 with relation to the stationary blower head 83. The valve 84 is mounted in a seat 85 in the stationary head 83 and any rocking movement is taken care of by the spherical bearing 86 mounted on the blower pipe 20 and seating on the spherical bearing seat 86a. The sheave wheel 90 may be mounted rigidly on the valve part 84, while the sleeve 82 may be 50 keyed to the end 20a of the blower pipe 20

as by a key 91. The blower pipe 20 is rotatably supported from the boiler tubes 22 by means of bearings 87 and longitudinal movement of the blower pipe 20 is substantially prevented by collars 88 on opposite sides of 70 the bearing portion 89.

I do not, however, desire to limit the invention to the particular constructions shown, since various changes and further modifications will be apparent from a disclosure of 75 the particular constructions described.

What I claim as my invention is:—

1. In a boiler cleaner, the combination with a boiler wall and a blower pipe extending transversely through said wall, said blower pipe being provided with a nozzle for discharging a cleaning fluid against a surface to be cleaned, of a blower head mounting the blower pipe and having rigid supporting engagement with said boiler wall, means for turning said blower pipe about its longitudinal axis to direct the nozzle toward different portions of the boiler to be cleaned, and means affording yielding connection between said blower pipe and said blower head, said last mentioned means comprising a flexible diaphragm.

2. A boiler cleaner comprising in combination with a boiler wall and an opening therethrough a cleaning fluid chamber fixed with respect to the boiler wall, a blower element extending through said opening and having a ported end within the said chamber, means for rotating said element, a sleeve surrounding said end of the element and provided with a port adapted to register with the element port as the element is rotated with respect to the sleeve, and means affording a flexible connection between the sleeve and chamber.

3. A boiler cleaner comprising in combination with a boiler wall and an opening therethrough a cleaning fluid chamber fixed with respect to the boiler wall, a blower element extending through said opening and having a ported end within the said chamber, means for rotating said element, a sleeve surrounding said end of the element and provided with a port adapted to register with the element port as the element is rotated with respect to the sleeve, and means affording a flexible connection between the sleeve and chamber, said means comprising a flexible diaphragm.

4. In a boiler cleaner, a blower head, a rotatable cleaner element journaled in said head, and a valve carried by said cleaner element within said head, the said valve and cleaner element being floated with respect to the head.

5. In a boiler cleaner, a blower head, a cleaner element, means for rotating said element a sleeve valve surrounding said element, and a yieldable corrugated connection between said sleeve valve and said head permitting relative universal movement.

6. In a boiler cleaner, a blower head, a flexible extension fitted to said head, a blower element mounted to rotate in said flexible extension, and means to rotate said blower element.

7. In a boiler cleaner, a blower head, a flexible corrugated member secured to one wall of said head and projecting interiorly of the head, and a blower element mounted to rotate in said flexible corrugated member.

8. In a boiler cleaner, a blower head, a sleeve valve yieldably supported by said head and within the same, and a blower element journaled in said sleeve valve.

15 9. In a boiler cleaner, a blower head, a sleeve valve within said head, a flexible corrugated member supporting said sleeve valve from said head, and a blower element journaled in said sleeve valve.

20 10. In a boiler cleaner, a blower head, a valve yieldably supported within said head for floating movement therein, and a blower element having a port controlled by said valve, said blower element being mounted for 25 floating movement within the head with the said valve.

11. In a boiler cleaner, a blower head, a valve member within said head, a flexible corrugated member connecting said valve member to said head whereby said valve member is mounted for floating movement within said head, and a blower element having a port controlled by said valve, the said blower element being mounted for floating 35 movement within the head with the valve.

12. In a boiler cleaner, a movable blower element, means carried by said blower element for moving the same to direct jets of cleaning fluid from the blower element ad-

40 jacent portions of the boiler to be cleaned, means including a blower head for supplying cleaning fluid to the blower element, and a yieldable connection between said blower head and said blower element providing for 45 relative movement between the axes of said blower head and blower element in parallel planes.

13. In a boiler cleaner, a movable blower element, means for moving said blower element to direct jets of cleaning fluid from the same adjacent portions of the boiler to be cleaned, means including a head for supplying cleaning fluid to said blower element, and a valve operable in timed relation to the 55 movement of said blower element for controlling the flow of cleaning fluid to the blower element, said valve and blower element being mounted for floating movement with respect to said blower head.

60 14. In a boiler cleaner, a blower head, a rotatable blower element extending into said head, said blower element being formed with a laterally opening port located in the portion of the blower element 65 extending within the head, a cylindrically

surfaced valve seating on the blower element for controlling the flow of cleaning fluid through said port, and means including a yieldable member disposed between the valve and the blower head for yieldably mounting 70 said valve.

15. In a boiler cleaner, a blower head, a rotatable blower element extending into said head, said blower element being formed with a laterally opening port located 75 in the portion of the blower element extending within the head, a cylindrically surfaced valve seating on the blower element for controlling the flow of cleaning fluid through said port, and means including a yieldable member disposed between the valve and the blower head arranged to provide for movement of the valve in a plane perpendicular to the axis of the 80 blower element.

16. In a boiler cleaner, a blower head, a rotatable blower element extending into said head, said blower element being formed with a laterally opening port located 90 in the portion of the blower element extending within the head, a cylindrically surfaced valve seating on the blower element for controlling the flow of cleaning fluid through said port, means including a yieldable member disposed between the 95 valve and the blower head for yieldably mounting said valve, means for rotating the blower element, and means for restraining said valve against rotation with the blower element to provide for the uncovering of said 100 port upon rotation of the blower element to admit cleaning fluid to the blower element.

In testimony whereof I affix my signature.
